UNITED STATES PATENT OFFICE.

LINK SMITH, STEPHEN D. MCOSKER, AND JAMES R. SIMPSON, OF ENID, OKLAHOMA.

DETACHABLE HEEL.

1,307,423.

Specification of Letters Patent. Patented June 24, 1919.

Application filed May 17, 1918. Serial No. 235,178.

To all whom it may concern:

Be it known that we, LINK SMITH, STEPHEN D. MCOSKER, and JAMES R. SIMPSON, citizens of the United States, residing at Enid, in the county of Garfield and State of Oklahoma, have invented certain new and useful Improvements in Detachable Heels, of which the following is a specification.

This invention relates to the shoe heels, 10 more particularly to heels of rubber or like material, and has for one of its objects to provide a device of this character which may be readily applied to the shoe by any person without previous skill or knowledge, 15 and which may be readily detached for renewal or repair without discarding the remainder of the shoe.

With these and other objects in view, the invention consists in certain novel features 20 of construction, as hereinafter shown and described and then specifically pointed out in the claims; and in the drawings illustrative of the preferred embodiment of the invention—

25 Figure 1 is a perspective view of the heel portion of a shoe with the improved heel applied.

Fig. 2 is a sectional elevation,

Fig. 3 is a detached perspective view of 30 the metal anchor plate.

The improved device comprises a heel formed of rubber or like material and having a plate embodied therein with spurs projecting from the plate through the upper face of the heel and adapted to enter the heel portion of the sole of the shoe and support the heel from horizontal displacement. The plate which is embedded within the body of the heel is formed with a threaded 35 aperture to receive a holding screw which is passed through the heel portion of the sole of the shoe and the intervening portion of the rubber heel and into the threaded aperture of the plate. By this means the heel is 40 firmly connected to the heel portion of the sole, and can be quickly applied or removed for renewal or repairs.

In the drawings a portion of a shoe is shown including the body 10, the sole 11, 50 and the insole 12. The improved device may be applied without material structural change to different structures of shoes, and it is not desired to limit the invention to any specific form or size of shoe. The heel portion of the shoe is represented as a whole at 13 and is molded into the required shape

from rubber or like material, preferably the same composition usually employed in the manufacture of rubber heels. The holding plate above referred to is represented at 14 60 and is embedded or vulcanized within the body of the material of the heel as illustrated in Fig. 2. The plate 14 is increased in thickness at the center and the thickened portion provided with a threaded aperture represented at 15 to receive the threaded terminal of a holding bolt or screw 16. The bolt extends through the upper portion of the heel and through the heel portion of the sole 11 covered by the insole 12. The upper end 70 of the bolt is laterally enlarged in flat form as shown at 17, the enlarged portion forming the head of the bolt as shown. The head 17 is provided with a screw-driver receiving slot, so that the bolt may be rotated to draw 75 the heel 13 firmly into engagement with the sole of the shoe and firmly support it from displacement. The sole 11 is slightly recessed adjacent the aperture for the bolt to receive the lower face of the head 17, 80 while the lower face of the insole 12 is likewise recessed to receive the curved outer face of the head. By this means the bolt head does not produce a protuberance or projection at the heel of the shoe. The plate 14 85 is provided with a plurality of relatively sharp tongues 20, preferably formed by cutting V-shaped clefts through the plate and bending the material between the clefts substantially at right angles to the face of the 90 plate. The tongues are designed to project through the intervening portion of the body of the heel 13 and enter the sole 11 of the shoe, to hold the heel from horizontal displacement, and coact with the bolt 16 to hold the 95 heel in place. The plate 14 is likewise provided with numerous relatively large apertures 21 into which the material of the heel will enter during the vulcanizing process to further anchor the plate within the material of the heel. 100

The improved device is simple in construction and can be manufactured and furnished to the trade ready to be applied in place of the ordinary heel and without change in the 105 structure of the shoe except the relatively slight aperture and recesses in the sole portions to receive the bolt 16 and its head 17.

Having thus described the invention, what is claimed as new is:

1. As a new article of manufacture, a rubber heel comprising a body portion and a

single flat relatively thin reinforcing plate of the general contour of the heel embedded in the body portion near the attaching face thereof and provided with a plurality of upstruck substantially V-shaped spurs disposed on one side of the plate only and spaced inwardly from the marginal edge thereof with certain of the spurs extending diagonally across the breast corners of the plate, said spurs being arranged in triangular form with the points of the spurs normally projecting through and beyond the attaching face of the heel, the central portion of the plate being thickened and provided with a centrally disposed threaded opening for the reception of a fastening device, there being a plurality of openings formed in said plate between certain of the spurs and disposed concentric with the central opening and a plurality of smaller openings extending entirely around the plate near the marginal edge thereof.

2. The combination with a shoe including an outer sole and an inner sole, the confronting faces of which are formed with registering depressions, of a rubber heel having a

single reinforcing plate of the general contour of the heel embedded therein near the attaching face thereof and having its central portion enlarged and provided with a threaded opening, the body of the plate being formed with upstruck substantially V-shaped anchoring spurs spaced inwardly from the marginal edge of the plate and arranged in substantially triangular form with certain of said spurs extending diagonally across the breast corners of said plate, the points of the spurs being disposed on one side of the plate only and normally extending through and beyond the attaching face of the heel and into the outer sole of the shoe, and a securing element having its lower end threaded for engagement with the threaded opening in the plate and its upper end provided with an enlarged head seated in the depressions in the outer and inner soles, respectively.

In testimony whereof we affix our signatures.

LINK SMITH. [L.S.]
STEPHEN D. McOSKER. [L.S.]
JAMES R. SIMPSON. [L.S.]
